(57) **CLAIM**

The ornamental design for a combined surgical navigation system monitor and stand, as shown and described.

DESCRIPTION

FIG. 1 is a perspective view of a combined surgical navigation system monitor and stand showing our new design; FIG. 2 is a first side view thereof;

FIG. 3 is a second side view thereof;

FIG. 4 is a front view thereof;

FIG. 5 is a rear view thereof;

FIG. 6 is a top view thereof; and,

FIG. 7 is a bottom view thereof.

The broken lines depict portions of the combined surgical navigation system monitor and stand that form no part of the claimed design.
